UNITED STATES PATENT OFFICE.

WILLIAM M. LENNAN, OF TORONTO, ONTARIO, CANADA.

DIESTOCK LUBRICATOR.

1,410,329.

Specification of Letters Patent. Patented Mar. 21, 1922.

Application filed October 8, 1919. Serial No. 329,323.

To all whom it may concern:

Be it known that I, WILLIAM M. LENNAN, a citizen of the United States of America, and resident of the city of Toronto, county 5 of York, Province of Ontario, in the Dominion of Canada, have invented certain new and useful Improvements in Diestock Lubricators, described in the following specification and illustrated in the accompanying drawings, that form part of the same.

The principal objects of the invention are, to facilitate the oiling of the chasers of a pipe threading tool, and to devise a simple 15 and efficient form of oiling device which may be attached to any die stock and will effect a very material saving of the mechanic's time and will also save considerable oil.

20 The principal feature of the invention consists in the novel construction of an oiling chamber adapted to be attached to the die stock at one of the handle fittings and of the novel means of controlling the flow of 25 oil from the chamber.

The drawing represents a longitudinal mid-sectional view of my improved device.

Various forms of lubricating devices for 30 die stocks have been proposed but such devices as far as I am aware are extremely limited in their oil capacity and either require a special construction of die stock or are quite complicated and therefore expensive and in view of these conditions are 35 objectionable and it is the purpose of this invention to provide a simple, effective and inexpensive device.

Referring to the accompanying drawing, the die stock 1 is of the ordinary type having 40 the threaded lug extensions 2 to which the handles are secured which handles are ordinarily formed of a length of pipe.

My improved device is adapted to be inserted into one of the handle lugs and it consists 45 of a threaded shank 3 threaded into the lug 2 having an enlarged outer end 4 which forms the head of the oil chamber.

The oil chamber is formed of a cylindrical shaped casing 5 threaded on to the head 50 4 and having its outward end 6 reduced to form the handle extension.

A piston 8 is arranged within the oil chamber 5 and connected thereto is a stem 9 which extends into the handle extension 6 and has

secured to its outer end a block 10 which 55 slides freely within the handle.

The handle 6 is provided with a longitudinal slot 11 having a notch 12 in one side thereof at the outer end and a pin 13 is secured in the block 10 and extends through 60 said slot. This pin is provided for the purpose of drawing the piston to the outward end of the oil chamber which may be held in the outward position by turning the pin in the notch 12. 65

A spiral spring 14 is arranged within the inner end of the oil chamber and engages the piston and is adapted to move the piston toward the head end of the oil chamber when the pin 13 is released from the notch 12. 70

The head 4 is provided with an opening 15 through which a supply of oil is placed in the chamber 5 being closed by a threaded plug 16.

The head 4 is also provided with an 75 oblique opening 17 communicating with the interior of the oil chamber. This opening is provided with a small central hole 18 at the outer end in which a valve stem 19 is supported. 80

The valve stem extends through the opening 17 and is provided with a valve 20 at the inner end adapted to close the opening.

It will be noted that the pressure placed upon the oil within the chamber 5 by the 85 spring 14 acts against the valve 20 to hold it closed. A coil spring 21 encircles the outer end of the valve stem 19 under the head 22 and ensures the closing of the valve. 90

A hole 23 connects with the oblique opening 17 and extends to the outer face of the head and a small pipe 24 is secured in the enlarged outer end of this hole and extends over the die stock, the terminal end thereof being turned inwardly toward the tool and 95 arranged to direct the oil upon the chasers.

In order to apply this device to a die stock it is merely necessary to remove the oil pipe 24 and after removing the handle from the die stock inserting the lug 3 and locking it 100 in position by means of the lock nut 25. The oil pipe 24 is then placed in position and bent to direct the oil into the proper place. The piston is then drawn up by means of the pin 13 and locked in its outward position against the pressure of the spring 14. The plug is then removed from the opening 105 15 and the oil chamber is filled with oil.

The plug is again replaced and the device is ready for use. The pin 13 is released from the notch 12 and the spring 14 creates a pressure upon the oil within the chamber.

5 When the operator desires to place oil upon the chasers in the die he merely presses upon the head 22 of the valve stem 19, thus moving the valve 20 from its seat and the oil under pressure flows out through the 10 opening 17 and hole 23 to and through the pipe 24. Immediately the valve 20 is released the spring 21 together with the pressure acting against the valve closes the same and stops the flow of oil.

15 It will be seen from this description that the device is extremely simple; it is very positive in its action and will ensure the placing of the oil where required and whenever required as well as giving the desired 20 quantity. The oil chamber contains a considerable supply of oil rendering it unnecessary to refill the same, while the die is being used and a supply of oil is positive no matter what position the handle formed by 25 the oil container may be in. No alteration to the die stock is required and it may be therefore attached to any standard stock,

requiring no machining or alteration of any kind.

What I claim as my invention is:—

1. A die stock lubricator, comprising an oil chamber, spring actuated means for maintaining a constant pressure upon the oil within said chamber, means for locking said spring means from exerting pressure on the oil, an oil tube leading from said chamber to the die stock, and a valve for controlling the flow of oil through said tube.

2. A die stock lubricator, comprising, a cylindrical oil chamber, a piston in said oil chamber, a stem secured to said piston and extending beyond said oil chamber, a slotted tube extension from said oil chamber having a notch, a pin connected to said piston stem sliding in said slot and adapted to engage said notch, a coil spring encircling the stem within the oil chamber and exerting pressure against said piston, an oil passage from the opposite end of the oil chamber, a valve controlling said oil passage, and an oil tube leading from said oil passage to the die stock.

WILLIAM M. LENNAN.
